UNITED STATES PATENT OFFICE

166,168

ELECTRIC LAMP OR SIMILAR ARTICLE

John C. Balyozian, Arlington, Mass.

Application April 3, 1951, Serial No. 14,705

Term of patent 7 years

(Cl. D48—20)

To all whom it may concern:

Be it known that I, John C. Balyozian, a citizen of the United States, residing at Arlington, in the county of Middlesex, in the Commonwealth of Massachusetts, have invented a new, original, and ornamental Design for an Electric Lamp or Similar Article, of which the following is a specification, reference being had to the accompanying drawing, forming a part thereof, in which:

Fig. 1 is a front elevational view of an electric lamp or similar article, showing my new design.

I claim:

The ornamental design for an electric lamp or similar article, substantially as shown.

JOHN C. BALYOZIAN.
